UNITED STATES PATENT OFFICE.

WILHELM A. BOHM AND WILHELM A. BOHM, JR., OF BALTIMORE, MARYLAND.

TOILET-SEAT.

1,227,373.

Specification of Letters Patent.

Patented May 22, 1917.

Application filed August 18, 1916. Serial No. 115,682.

To all whom it may concern:

Be it known that we, WILHELM A. BOHM and WILHELM A. BOHM, Jr., subjects of the Emperor of Austria, residing at Baltimore, 5 in the State of Maryland, have invented certain new and useful Improvements in Toilet Seats; and we do hereby declare the following to be a full, clear, and exact description of the invention, such as will enable others skilled in the art to which it app- 10 pertains to make and use the same.

This invention relates to toilet seats, and an object of the invention is to dispense with the ordinary type of seat now in use and to 15 substitute therefor one that will be sanitary and comfortable and will be of simple construction and can be conveniently associated with the toilet bowl.

Another object of the invention is the 20 provision of a seat of this nature that will overlie the forward end of the toilet bowl and will prevent the person's body from coming in contact with the bowl, the said seat having associated therewith a web of 25 paper adapted to be passed over the upper side of the seat so as to admit of a clean surface being had for each person.

Other objects will appear and be better understood from that embodiment of my invention of which the following is a specification, reference being had to the accompanying drawings forming a part thereof, in which:

Figure 1 is a top plan view of a toilet 35 bowl and the new type of seat associated therewith,

Fig. 2 is a side view of the toilet bowl and the seat,

Fig. 3 is a front view of the toilet seat, 40 showing the housing for inclosing the web of paper in section,

Fig. 4 is a sectional view, taken through the housing for the paper web and the seat,

Fig. 5 is a detail sectional view of the 45 crank mechanism for imparting movement to the paper web,

Fig. 6 is a section taken on the line 5—5 of Fig. 5,

Fig. 7 is a section taken through one end 50 of the roller upon which is to be wound the soiled portion of the paper web, and

Fig. 8 is a perspective view of the housing for inclosing the web.

Referring to the drawings in detail, the 55 letter A designates a toilet bowl of usual construction. Located at the rear end of

the upper edge of the bowl A is a pair of spaced vertically disposed ears 2, and journaled within the ears 2 is a horizontal shaft 3. A pair of supporting levers 4 are located 60 at the opposite sides of the bowl A and are inclined upwardly and have their upper ends continued in parallelism, as shown at 5, and connected to the opposite ends of the shaft 3. The forward ends of the levers 4 are ex- 65 tended beyond the forward side of the bowl A and terminally extended upwardly, as shown at 6, and interposed between the terminals of the forward ends of the levers 4 is a rectangular shaped ledge 7, which is 70 designed to provide a seat and to take the place of the ordinary ring seat now in use. The shaft 3 is provided, at a point between the ears 2, with an upwardly and outwardly curved finger 8, and connected to the finger 75 8 is the upper end of a contractile spring 9, the lower end of the spring 9 having connection, as shown in Fig. 2, with a hook 10 which projects outwardly from the rear side of the bowl A. When the seat 7 is occ- 80 cupied, it is depressed and causes the spring 9 to be expanded, so that when the seat is relieved of weight the spring 9 will return the seat into the position shown in Fig. 2. The seat 7 extends only across the forward 85 end of the upper edge of the bowl A so that the occupant's body will not contact with any portion of the bowl A.

Positioned at the forward end of the bowl A and at a point below the seat 7 is a hous- 90 ing 11, having its top and rear side open, as shown in Fig. 8 of the drawings. The housing 7 is adapted to be supported between the forward ends 6 of the levers 4 and the side walls of the housing are provided with upper 95 and lower pairs of slots 12, the inner ends of which are enlarged to provide bearing por- tions 13. A roller 14 is removably supported in the upper pair of slots 12 and has formed thereon a web of paper 15, the end of the paper being extended over the upper side of the seat 7 and thence downwardly around the guide 16 which is carried by the housing, and then around another roller 17. The shaft of the roller 14 is supported in the 100 uppermost pair of slots 12 and the shaft of the roller 17 is journaled in the lowermost pair of slots 12, as shown in Fig. 4. The roller 17 has a longitudinal slot 19 formed in the periphery thereof, as shown in Fig. 105 7, and is adapted to receive the end of the paper web, and an anchoring strip 18 is re-

ceived by the slot 19 and is adapted to retain the end of the paper web in position, so that when the roller 17 is rotated the web of paper will be caused to be wound thereupon. The anchoring strip 18 is held in position by means of semicircular clips 20, which engage partially around the roller 17 and overlie the strip 18, as shown more particularly in Fig. 7. A crank handle 21 is operatively connected with the roller 17, so that the roller 17 can be conveniently rotated to admit of the web being wound therearound. The paper web 15 serves to provide a clean surface for each occupant and as that portion of the web that is presented to the upper side of the seat becomes soiled, the roller 17 is rotated so as to partially wind the web thereon, and cause a clean portion to be presented to the upper side of the seat 7.

The inner longitudinal edge of the seat 7 overlies the forward end of the upper edge of the bowl A, so as to admit of the bowl A forming a stop to limit the downward movement of the seat 7 under the weight of a person, thereby relieving the shaft 3 and the levers 4 of considerable strain. By virtue of the employment of the shaft 3 the forward ends of the levers 4, and the seat 7 can be raised upwardly, similar to the ordinary toilet seat, when desired.

It is evident that various changes might be resorted to in the construction, form and

arrangement of the several parts without departing from the spirit and scope of our invention.

Having thus described our invention what we claim as new, is:

1. The combination with a toilet bowl, of a pair of levers associated with the bowl, a seat carried by the levers, a housing carried by the levers and disposed below the seat, and a paper web extended from the housing and operable across the seat, for the purpose specified.

2. The combination with a toilet bowl, of a pair of supporting elements lying on opposite sides of the bowl and having their forward ends extended beyond the forward end of the bowl and extended upwardly and terminally lying above the bowl, a seat disposed above the forward edge of the bowl and supported by the upwardly extended end of the supporting element, a roller operatively supported by the upwardly extending ends of the supporting element and disposed below the seat, and a paper web carried by the roller and extended across the seat.

In testimony whereof we affix our signatures in presence of two witnesses.

WILHELM A. BOHM.

WILHELM A. BOHM, JR.
